Primary Examiner — Ruth McInroy(74) *Attorney, Agent, or Firm* — John Yun(57) **CLAIM**

The ornamental design for a steam cleaning floor head, as shown and described.

DESCRIPTION

FIG. 1 is a perspective view of a steam cleaning floor head showing my new design;

FIG. 2 is a front view thereof;

FIG. 3 is a rear view thereof;

FIG. 4 is a right view thereof;

FIG. 5 is a left view thereof;

FIG. 6 is a top plan thereof; and,

FIG. 7 is a bottom plan view thereof.

The details shown in broken lines form no part of the claimed design.
